Duke Arnold of Providence R.I.

Letter Patent No 528. Dated Nov 30th 1839.

mmmmmm

The schedule referred to in these Letter Patent and making part of the same.

mmmmmm

To all Persons to whom these Presents shall come,

Be it known that I

Duke Arnold of Providence in the County of Providence and State of Rhode Island have produced a new and original design for a parlor stove and I hereby declare that the said new design is fully described and represented in the following specification and accompanying drawings to which reference is hereinafter made.

The figures of the accompanying plates of drawings represent my new design. In Plate 1 fig 1 is an elevation of the front plate, and fig 2 an elevation of the back plate. In plate 2 fig 3 is a plan of the top plate, fig 4 a vertical section of the same taken in the plane of the line A.B. fig. 3 fig 5 is an elevation of the end plate and fig 6 a section of the same taken in the plane of the line C.D. fig 5.

The top and bottom of the front plate are ornamented with the raised pieces a.a &c. the centre being occupied by two arched panels b. b. c. c in which are the raised figures of a woman d. and a man e. e. with foliage j j in the background of each. Over each panel is placed drapery f f.

The back plate is ornamented with the pieces a.a &c and two arched panels g g - g g in each of which are the figures of a boy and girl h. h.

The top plate has around it the raised pieces i i &c. K &c and four pieces of leaf work l. l. l. l.

The end plate is ornamented with the pieces a.a &c and the arched panel m. m. in which are the figures of a woman and child n. o. with foliage p. p. in the background.

Having thus described my new design I shall state my claim as follows

What I claim as my production and desire to have secured to me by Letter Patent is the new design consisting of the ornamental configurations and raised figures herein above described and represented in the drawings for a parlor stove.
